LYMAN L. WEBSTER, OF FRANKLINVILLE, NEW YORK.

RAIL-TIE SUPPORT.

Application filed August 5, 1926. Serial No. 127,365.

This invention relates to an improved article of manufacture which may be conveniently described as a rail tie support.

The invention has more particular reference to a railway appliance of this class which is adapted for use more particularly beneath a rail joint.

Usually, where a rail joint occurs in the track, the incessant pounding of the wheels 10 of the cars upon this track causes the rail end to sag slightly. This is due partially to the sinking of the ties into the comparatively soft road bed.

What I aim to do is to provide a novel, 15 simple, and inexpensive structure to extend beneath several of the ties adjacent the rail joint for maintaining these ties in alignment and preventing, to a limited extent, sinking of the same in the ground.

The particular construction for accomplishing this result will become apparent 20 from the following description and drawings.

In the drawings:—

Figure 1 is a top plan view of a fragmentary portion of a railway track structure showing the improved support associated therewith;

Fig. 2 is a side elevation of the same;

Fig. 3 is a perspective view of the device per se.

In the drawings, the reference characters 1 and 2 designate the rail ends which are shown connected together by customary fish plates 3. The rail tie 4 beneath these joints and the two ties on opposite sides of the joints are designated by the reference characters 4, and it is these ties that the improved device serves to support in particular.

Adjacent ties 5 cooperate in accomplishing this result. The device per se is designated by the reference character 6 and it comprises a sturdy metal plate 7 which, in practice, is about one foot in width. The opposite end portions of this plate are directed upwardly at right angles as at 8 and the extremities are directed at right angles to the portions 8 as at 9 in order to extend 50 in parallelism with the body portion 7.

These portions 9 constitute what may be conveniently designated as attaching ears, and it will be noticed that they are provided with elongated slots 10 for passage of the

customary spikes 11. The reference character 12 designates insulators which are disposed between the base of the rail and the metallic end of the ears, to prevent grounding of the current which is sometimes passed through the rail.

In practice the central body portion 7 of the plate is disposed beneath the under sides of the ties 4, thus bringing the shoulder forming portions 8 in contact with vertical faces of the ties 5 and permitting the attaching ears 9 to rest upon the tops of the ties 5. The device is fastened in place by the same spikes which serve to hold the rail ends in position. The purpose of the slots is to allow some slight lateral play of the 70 device to accommodate irregularities in the rail and to permit the device to be used on slight curves.

The device is of such utmost simplicity that the construction and method of application will undoubtedly be clear after considering the description in connection with the drawings. Consequently, a more lengthy description is thought to be unnecessary.

It might be added, however, that the device functions somewhat as a truss, equally distributing the stresses and strains, and prevents embedding of the tie ends of the comparatively soft road bed.

Having thus described my invention, what I claim as new is:—

In a structure of the class described, in combination, a railway track including a plurality of rail supporting ties disposed in usual spaced relation, rail ends supported upon said ties and having their adjacent ends in approximate abutting relationship, a rail joint between said ends; and a support comprising an elongated plate under the intermediate ones of said plurality of ties and having its end portions directed upwardly at right angles to provide shoulders for abutting the end ones of said plurality of ties and having its extremities disposed at right angles to said shoulders to form attaching ears to be engaged with said end ones of said plurality of ties on the tops thereof, said ears being provided with apertures for passage of retaining spikes.

In testimony whereof I affix my signature.

LYMAN L. WEBSTER.
